UNITED STATES PATENT OFFICE.

JULIETTE L. PHILIPPEAU, OF NEW YORK, N. Y.

DESIGN FOR A BEVERAGE DISPENSER.

Application filed July 6, 1928. Serial No. 27,400. Term of patent 14 years.

To all whom it may concern:

Be it known that I, JULIETTE L. PHILIPPEAU, a citizen of the United States, residing at New York, in the county of New York and State of New York, have invented a new, original, and ornamental Design for Beverage Dispenser, of which the following is a specification, reference being had to the accompanying drawing, forming part thereof.

The figure is a perspective view of a beverage dispenser showing my new design.

I claim:

The ornamental design for a beverage dispenser as shown.

JULIETTE L. PHILIPPEAU.
